Hardway & Cather ^{Attorneys}

UNITED STATES PATENT OFFICE.

MAX F. DE BAJLIGETHY, OF HOUSTON, TEXAS.

STILL.

Application filed April 7, 1922. Serial No. 550,342.

To all whom it may concern:

Be it known that I, MAX F. DE BAJLIGETHY, citizen of the United States, residing at Houston, in the county of Harris and State of Texas, have invented certain new and useful Improvements in a Still, of which the following is a specification.

This invention relates to new and useful improvements in a still.

10 One object of the invention is to provide a still specially designed for use in the distillation of hydrocarbon oils and whereby the elements of low gravity may be separated from the heavier elements.

15 Another object of the invention is to provide a still of the character described which is of very simple construction and may be cheaply and easily manufactured and which will be very effective in extracting from the hydrocarbon oils a high percentage of the 20 low gravity elements.

With the above and other objects in view the invention has particular relation to certain novel features of construction, operation 25 and arrangement of parts, an example of which is given in this specification and illustrated in the accompanying drawings, wherein:—

Figure 1 is a fragmentary plan view of 30 the still shown partially in section and,

Figure 2 is a vertical sectional view.

Referring now more particularly to the drawings, the numeral 1 designates a boiler under which there is a furnace 2. The boiler is filled with hydrocarbon oils through the inlet line 3 which is controlled by the valve 4. The numeral 5 designates a vat in which there is the condensing coils 6 which discharge the distillate into a suitable receiving tank 7. The vat 5 is preferably filled with water to keep the coil cool so as to cause condensation therein.

The boiler 1, on each side is formed with relatively high cylindrical domes 8, 8 one at 45 each end. These domes have the central flues 9, 9 which are fastened at their upper ends to the top of the domes and have inlet openings as 10. These flues depend into the boiler and their lower ends are connected by 50 a connecting pipe 11, which is normally submerged in the hot fluid in the boiler and leading from this common pipe 11 to the central dome 12, of the boiler there is a pipe 13. The dome 12 is connected into the 55 coil 6 through a line 14, which is controlled by the valve 15.

Within the domes 8 there are the vertical disc like inverted conical shaped perforated baffles 16 spaced apart. These baffles are anchored at their outer edges to the domes 8 and at their inner edges to the flues 9 and opposite each baffle there is secured around each dome the annular radiating plates 17. These plates radiate the heat and keep the baffles 16 comparatively cool. The fluid in the boiler is kept at a high degree of temperature and the lighter elements are constantly being given off and pass up through the perforated baffles and enter the upper ends of the flues 9 and then pass downwardly through said flues and through the pipes 11 and 13 into the dome 12 and thence out through the line 14 into the coil 6, where they are condensed and through which they enter the receptacle 7. The vapors passing through the pipe 11, which is very hot, are further broken down, thus facilitating the process of distillation. The heavier particles are arrested by the baffles 16 and drop back into the boiler to be again broken up by the heat therein, the lighter elements constantly passing up through the domes 8 and the heavier elements being arrested and dropping back into the boiler. A very high percentage of the hydrocarbon oil in the boiler is thus distilled and the lighter elements are extracted therefrom.

What I claim is:—

1. An oil cracking still including a boiler, a dome upstanding therefrom and whose upper end is closed, a flue within said dome secured at its upper end to the closed end of the dome and whose upper end is provided with an inlet and whose lower end extends down into said boiler, a pipe within the boiler, normally submerged in the fluid therein, into which the lower end of the flue connects, said pipe leading outside of the boiler, a plurality of baffles between said flue and dome and heat radiating members carried by the periphery of the dome.

2. An oil cracking still including a boiler, a dome upstanding therefrom whose upper end is closed, a flue within said dome having an inlet opening, baffles between the flue and dome, heat radiators carried by the periphery of the dome, and a conduit passing through the boiler with which the flue connects.

3. An oil cracking still for oil and the like including a boiler, a dome having an inlet opening upstanding therefrom, a flue

within said dome and foraminated baffles surrounding said flue in said dome.

4. An oil cracking still for oil and the like including a boiler, a dome having an inlet opening upstanding therefrom, a flue within said dome, and peripheral heat radiators carried by said dome.

5. An oil cracking still including a boiler, a plurality of domes upstanding therefrom whose upper ends are closed, flues within said domes each having an inlet opening, an outlet conduit within the boiler connected to said flues, a condensing coil outside of the boiler in which said outlet pipe terminates, foraminated baffles around the flues within the domes and peripheral, heat radiators carried by said domes.

6. An oil cracking still including a boiler, a dome upstanding therefrom, whose upper end is closed, a conducting pipe within the

boiler, said conducting pipe being arranged near the bottom of the boiler, a flue connected at its lower end to said conducting pipe and extending up into said dome and provided near its upper end with a vapor inlet, baffles arranged between said flue and dome, an outlet pipe connected into said conducting pipe and leading up through the top of the boiler, a condensing coil outside of the boiler in which said outlet pipe terminates, and a valve controlling said outlet pipe.

In testimony whereof I have signed my name to this specification in the presence of two subscribing witnesses.

MAX F. DE BAJLIGETHY.
